(57) **CLAIM**

I claim the ornamental design for a beverage dispensing system, as shown and described.

DESCRIPTION

FIG. 1 is an assembled front, top and side perspective view of the beverage dispensing system embodying the design of the present invention in the open condition.

FIG. 2 is a side elevational view thereof in the closed condition, the side opposite being identical to the side shown in FIG. 2.

FIG. 3 is a front elevational view thereof in the closed condition.

FIG. 4 is a rear elevational view thereof in the closed condition.

FIG. 5 is a top plan view thereof in the closed condition.

FIG. 6 is a bottom plan view thereof; and,

FIG. 7 is an exploded perspective view of the beverage dispensing system embodying the present invention in the closed condition.
